UNITED STATES PATENT OFFICE.

THADDEUS B. LESZCZYNISKI, OF CHICAGO, ILLINOIS.

CHAIR-FAN.

1,262,525.

Specification of Letters Patent. Patented Apr. 9, 1918.

Application filed February 26, 1917. Serial No. 150,965.

To all whom it may concern:

Be it known that I, THADDEUS B. LESZCZYNISKI, a citizen of the United States, and a resident of Chicago, in the county of 5 Cook and State of Illinois, have invented a new and Improved Chair-Fan, of which the following is a full, clear, and exact description.

This invention relates to fans and particularly to an improved chair fan, and has 10 for an object the provision of an arrangement whereby a slight movement of the chair to which the device is connected will cause the proper operation.

Another object in view is to provide a 15 fan for a chair which includes a freely swinging fan member and a support rigidly connected to the chair so that when the chair is oscillated or rocked back and forth 20 the fan will be waved.

A still further object in view is to provide an improved clamp for clamping a 25 chair, the same being arranged to hold a fan support or umbrella, as occasion may demand.

In the accompanying drawings:

Figure 1 is a side view of a device embodying the invention, the same being shown applied.

Fig. 2 is a detail perspective view of the 30 fan member and the horizontal supporting bar therefor.

Fig. 3 is a section through Fig. 1 on line 3-3, the same being on an enlarged scale.

Fig. 4 is an enlarged edge view of the 35 clamp shown in Fig. 1.

Fig. 5 is a sectional view through Fig. 4 on line 5-5.

Referring to the accompanying drawings 40 by numerals, 1 indicates a rocking chair of any desired kind, to which the clamp 2 is secured, the same being held in place by a thumb screw 3 pressing against part of the back and forcing one of the clamping 45 jaws 4 against the back of the chair. Clamp 2 is arranged to support a bar 5 which may be solid or tubular as desired. If bar 5 is made tubular the upper end is provided with a bent-in section 6, as shown in Fig. 50 3, so as to accommodate the bent-in section 7 of the horizontal bar 8 whereby the parts are telescopically fitted together and are prevented from independent rotation. The bar 8 may be tubular or solid and may have 55 connected therewith a transverse bar 9 in any suitable way, as for instance, by hav-

ing the end 10 bent over or around the bar 9 or welded thereto. Bar 9 is provided with a ring 11 at each end, each of said rings having an opening 12 whereby the eyelets 60 13 and 14 may be threaded on to the rings as shown in Fig. 2 in order that the fan member 15 carrying the eyelets 13 and 14 may freely swing whenever the chair 1 is 65 rocked.

The clamp 2, as shown more particularly in Fig. 4, is provided with clamping jaws 4 and 4', jaw 4' carrying the clamping screw 3. Extending from jaw 4' is an arm 16, which arm is provided with a cup-shaped end 17 (Fig. 5) designed to receive the ball 18, which ball is provided with cut-away portions 19, 20, 21 and 22 merging together at the center, as shown, in Fig. 4, 70 said cut-away portions presenting notches 75 for receiving bar 5 or an umbrella when the device is used for holding an umbrella in position. A ring 23 is arranged in the ball 8, said ring being formed with an opening 24 and a threaded shaft 25, said threaded 80 shaft accommodating the wing nut 26. The shaft 25 extends through the bottom of the ball 18 and member 17 and through a washer 27 so that the bar 5 may be drawn toward 85 ball 18 and clamped in any of the notches 19 to 22, inclusive. The opening 24 is provided to accommodate the handle of an umbrella and not necessarily the bar 5. An ordinary umbrella or an umbrella used on the seashore is provided at one end with an 90 enlarged knob or handle and at the opposite end with a folding canopy so that the umbrella rod could not be threaded through a ring. For this reason the opening 24 is provided which will allow the shaft or 95 rod of the umbrella to be forced in side-wise and then the nut 26 tightened until the rod or shaft has been properly clamped.

What I claim is:

1. In a device of the character described, 100 a clamp for supporting an article comprising a supporting member provided with a rounded socket having an opening therein, a universally adjustable spherical shell arranged in said socket and provided with a 105 plurality of notches adapted to receive at different times the article to be supported, a ring member surrounding said article, ring member having a threaded extension projecting through said spherical shell and 110 through said opening, and a nut arranged on said threaded extension for drawing said

ring member toward said socket whereby the article will be firmly clamped in one of said notches.

2. In a device of the character described, 5 a clamp for supporting an article, said clamp comprising a spherical shell provided with a plurality of pairs of notches on one side for receiving said article, a ring having an opening in one side extending from

said spherical shell whereby the article may 10 be moved into the ring laterally and then moved into said notch, said ring member having a threaded extension, and a clamping nut engaging said threaded extension for drawing the ring member in such a direction as to cause said article to be pinched against the ball in any pair of said notches. 15

THADDEUS B. LESZCZYNISKI.
